METHOD AND DEVICE FOR POLISHING TWO EDGED RAZOR BLADES

Fritz Rohrbeck, St. Veit-on-the-Triesting,
Austria

Application December 11, 1930, Serial No. 501,704,
and in Austria January 14, 1930

2 Claims. (Cl. 51—212)

This invention relates to a device for sharpening two-edged razor blades or the like by means of some tool or body along which said razor blade is reciprocated in order to obtain keen edges. The known means for sharpening razor blades generally consist in using some grinding body or means which may be flat, cylindrical or trough shaped, and along which the blade to be sharpened is moved.

10 The sharpening of the blade in such a case is obtained by an operation which may be termed "grinding" and which may be best described by stating that the irregularities of the cutting edges are removed by severing and splitting off fine particles of the material during such operation.

Now it has been found that a particularly favorable sharpening effect can be obtained if the blade is moved over a brilliantly polished or highly burnished steel body which is trough-shaped, as a polishing agent; the blade is put on said polishing body in such a manner that both edges are resting upon the side walls of the trough.

25 The present invention is thus distinguished from the earlier art by the fact that a brilliantly polished steel surface is used, over which the blade is moved in a direction parallel to its cutting edges. Thus during this operation no splitting off or severing of fine particles will occur and the operation, therefore, may no longer be termed a grinding operation. The polishing effect is obviously due to other circumstances. The cutting edge of each plate, even if made of the best material and if very perfectly ground, has still certain irregularities which, though small, impair the keenness of the edge; moreover, the grinding action itself will cause certain irregularities of the structure of the edge, especially 35 receding parts or indentations due to the breaking and removing of crystalline particles. By moving the blade over the highly burnished or brilliantly polished steel trough in longitudinal direction all these slight irregularities are 40 smoothed by pressing the protruding parts into the plane or surface of the cutting edge and no indentations can be detected after the polishing operation according to this invention.

The new means of polishing allows to obtain 50 the necessary degree of cutting properties in a very simple manner and with a remarkable rapidity; it is quite sufficient to move a blade along the steel trough for a few times. The new device may be utilized not only for sharpening worn 55 blades, but may also be used with advantage

when manufacturing such blades and should be used as the last or finishing operation to give them the requisite degree of sharpness.

It is a most essential feature of this invention that the body necessary for polishing the blades 60 consists of steel of a sufficient grade or hardness and that it is brilliantly polished or highly burnished. A suitable material for the working surface is formed by sufficiently tempered steel, such as the usual steel with carbon or chromium or even of softer steels which have a chromium or 65 chromium alloyed surface.

The polishing surface to be used according to my invention has preferably the form of a cylindrical surface with its axis arranged in parallel 70 to the direction in which the working movement of the blade should take place. By these means simultaneous sharpening of both edges is obtained by merely moving the blade over the working surface under slight pressure, the clearance angle 75 between the working surface and the blade is thus automatically maintained during the whole operation.

In order to obtain a uniform treatment along 80 the whole cutting edge the working surface may be provided with rounded ribs running at an angle to the direction of movement of the blade, whereby a reiterated contact of all points of the edges of the blade even if deformed with the polishing surface is secured.

85 The invention is illustrated by way of example in the accompanying drawings in which Figs. 1, 2 and 3 are a longitudinal section, a cross-section and a plan of the device respectively while Fig. 4 is a longitudinal section through another modification of the invention.

90 As shown in Figs. 1, 2 and 3 the working surface of the polishing body is formed by a trough shaped body 1 of brilliantly polished steel, preferably provided with a cylindrical surface. This body 1 is fastened to a block 2 of wood or other suitable material by means of two bent ends 3 bent under a right angle which are entering into corresponding slots of said block.

95 For sharpening purposes the blade 4 which may be secured to a suitable holder, is moved to and fro in the direction of the arrow x.

According to Fig. 4 the polishing body 1 is 100 provided with a plurality of flat and rounded ribs running transversely to the direction of working movement of the blade and carefully rounded over 105 which the blade may easily slide.

What I claim is:

110 1. A device for sharpening two edged razor blades comprising trough shaped brilliantly pol-

ished, polishing surface, consisting of hard steel and having the form of a segment of a cylinder, said surface being provided with rounded ribs running at an angle to the axis of the cylinder.

5 2. A device for sharpening two edged razor blades, comprising a sheet consisting of brilliantly polished hard steel and having the form of a

segment of a cylinder, said sheet being bent at its ends, a block carrying said sheet of steel, the said sheet being secured to said block by its bent ends entering in corresponding slots of said block.
